(57) **CLAIM**

The ornamental design for a neck brace, as shown and described.

DESCRIPTION

FIG. 1 is a top perspective view of a neck brace in accordance with the invention;

FIG. 2 is a front view of the neck brace of FIG. 1;

FIG. 3 is a rear view of the neck brace of FIG. 1; and,
FIG. 4 is a side elevational view of the neck brace of FIG. 1; and,

FIG. 5 is a bottom plan view of the neck brace of FIG. 1.

The purpose of the broken lines in the drawings is to represent environmental features that form no part of the claimed design.
